UNITED STATES PATENT OFFICE.

MARSHALL WILFRED GLEASON, OF BROOKLYN, NEW YORK.

DESIGN FOR A GLOBE.

SPECIFICATION forming part of Design No. 28,689, dated May 24, 1898.

Application filed December 29, 1896. Serial No. 617,406. Term of patent 3½ years.

To all whom it may concern:

Be it known that I, MARSHALL WILFRED GLEASON, a citizen of the United States, and a resident of Brooklyn, county of Kings, and State of New York, have invented a new and original Design for Glass Globes or Shades, of which the following is a specification.

This invention has relation to designs for glass globes or shades, but relates more particularly to an ornamental configuration of a border therefor.

The design is fully shown in the accompanying drawings, in which—

Figure 1 is a side elevation of a globe or shade having my design for the border thereon. Fig. 2 is a plan view looking down upon the same from the smaller end thereof.

The leading feature of my design consists in a glass globe or shade having an ornamental border extending continuously around

its upper portion and comprising a series of alternating darts *c* and scrolls *d*, said scrolls facing alternately to the right and left.

The globe or shade herein shown is of pan or hemispherical shape and has regular flutings *A*, running radially from its flange *b* and with said border raised above or beyond the surface of said fluting. 25

Having thus described my invention, what I claim is— 30

The design for a globe, herein shown and described.

In testimony that I claim the foregoing as my invention I have signed my name, in presence of two witnesses, this 28th day of December, 1896. 35

M. WILFRED GLEASON.
